United States Patent Office

Des. 183,786
Patented Oct. 28, 1958

183,786

PHONOGRAPH TONE ARM OR THE LIKE

Robert R. Burdick and Maurice M. Palo, Conneaut, Ohio,
assignors to The Astatic Corporation, Conneaut, Ohio,
a corporation of Ohio

Application May 2, 1958, Serial No. 50,730

Term of patent 7 years

(Cl. D26—14)

Figure 1 is a top plan view of a phonograph tone arm or similar article, showing our new design;

Figure 2 is a side elevational view, the opposite side being a substantially mirror image thereof; and

Figure 3 is a perspective view thereof.

We claim:

The ornamental design for a phonograph tone arm or the like, as shown and described.
